CLAIM

The ornamental design for an image display device, as shown and described.

DESCRIPTION

FIG. 1 is a perspective view of the upper portion of the image display device, the base portion being omitted from the view; FIG. 2 is a side view of the upper portion of the image display device, the base portion being omitted from the view;

FIG. 3 is a top view of the upper portion of the image display device, the base portion being omitted from the view;

FIG. 4 is a bottom view of the upper portion of the image display device, the base portion being omitted from the view;

FIG. 5 is an exploded perspective view of the complete image display device;

FIG. 6 is a perspective view of the complete image display device;

FIG. 7 is an exploded view of the upper portion of the image display device, the base portion being omitted from the view;

FIG. 8 is a front view of the backing portion of the image display device, the body and the base being omitted from the view;

FIG. 9 is a side view of the backing portion of the image display device, the body and the base being omitted from the view;

FIG. 10 is a rear view of the backing portion of the image display device, the body and the base being omitted from the view;

FIG. 11 is a front view of the body of the image display device, the backing and the base being omitted from the view;

FIG. 12 is a side view of the body of the image display device, the backing and the base being omitted from the view;

FIG. 13 is a rear view of the body of the image display device, the backing and the base being omitted from the view;

FIG. 14 is a perspective view of the upper portion of a second embodiment of the image display device, the base portion being omitted from the view;

FIG. 15 is a side view of the upper portion of the second embodiment of the image display device, the base portion being omitted from the view;

FIG. 16 is a top view of the upper portion of the second embodiment of the image display device, the base portion being omitted from the view;

FIG. 17 is a bottom view of the upper portion of the second embodiment of the image display device, the base portion being omitted from the view;

FIG. 18 is an exploded perspective view of the complete second embodiment of the image display device;

FIG. 19 is a perspective view of the complete second embodiment of the image display device;

FIG. 20 is an exploded view of the upper portion of the image display device of FIGS. 14 and 19, the base portion being omitted from the view;

FIG. 21 is a front view of the backing portion of the image display device of FIGS. 14 and 19, the body and the base being omitted from the view;

FIG. 22 is a side view of the backing portion of the image display device of FIGS. 14 and 19, the body and the base being omitted from the view;

FIG. 23 is a rear view of the backing portion of the image display device of FIGS. 14 and 19, the body and the base being omitted from the view;

FIG. 24 is a front view of the body of the image display device of FIGS. 14 and 19, the backing and the base being omitted from the view;

FIG. 25 is a side view of the body of the image display device of FIGS. 14 and 19, the backing and the base being omitted from the view; and,

FIG. 26 is a rear view of the body of the image display device of FIGS. 14 and 19, the backing and the base being omitted from the view.

The broken lines illustrate environmental structure that forms no part of the claimed design.

The design is the shape and configuration of an image display device having a generally cylindrical body and an attachable backing portion.
